Term of patent 14 years

(Cl. D22—2)

To all whom it may concern:

Be it known that the undersigned, Walter E. Moore, a citizen of the United States, residing at Bel Nor, Missouri, has invented a new, original, and ornamental Design for a Can Opener Casing, of which the following is a specification, reference being had to the accompanying drawing, forming a part thereof, in which:

Fig. 1 is a top plan view of a can opener casing, showing my new design;

Fig. 2 is a front elevational view thereof;

Fig. 3 is a rear elevational view thereof;

Fig. 4 is an end elevational view thereof, looking from left to right in Fig. 2; and

Fig. 5 is an end elevation illustrating the other end thereof.

The essential features of my design reside in the portions shown in solid lines on the drawing.

I claim:

The ornamental design for a can opener casing, as shown and described.
